(Cl. D80—2)

FIG. 1

FIG. 2

FIG. 4

FIGURE 1 is a front perspective view taken from the top and one end of a counter top unit for banks or the like, showing my new design; the teller's window portion being in a closed position;

I claim:

The ornamental design for a counter top unit for banks or the like, substantially as shown and described.
